UNITED STATES PATENT OFFICE.

JOHN NILSSON, OF BROOKLYN, NEW YORK.

DESIGN FOR CASKET.

Specification forming part of Design No. 6,117, dated September 3, 1872.

Specification describing a Design for Caskets, invented by JOHN NILSSON, of Brooklyn, in the county of Kings and State of New York.

The nature of my design is fully represented in the accompanying drawing, to which reference is made, and in which—

Figure 1 is a top view, Fig. 2 a side view, and Fig. 3 an end view, of a casket constructed according to my design. Fig. 4 shows a dotted outline of an old form, which I do not claim, but merely show in order to better explain, by contrast, the distinctive feature of my design.

A is the casket, of which B is the cover. The longitudinal edges of the cover B may be parallel to each other, as seen in Fig. 1, or they may converge toward one end, as usual; but the ends of the cover, whether as seen in plan or end view, are formed of, preferably, three circle arcs on each side of the center line of the casket in the following manner: From a center, a , in the center line of the casket, with $a b$ for radius, is described the arc $b c$. On the line $a c$, connecting the center a with the extreme end e of the arc $b c$, is taken the center a' for the arc $c d$, described by the radius $a' e$. The line $a' d$, connecting the center a' with the extreme end d of the arc $c d$, is then extended beyond d , and on its extended portion a point, e , is taken as center for completing the curve from d to f . Thus is formed a continuous partly concave, partly convex, curve, the portion marked $d e b c d$ being the convex, and $f d d f$ the concave portions. If, with the point i for center and $i d$ for radius, the dotted circle-arc $d d$ were

drawn, the center e of the arc $d f$ would still lie on the extended radius $i d$ of the previous arc, and the half of the end of the cover B be an even curve of only two arcs; but I prefer three. In the drawing, the arcs $b c$, $c d$, $d f$ in the end view, in Fig. 3, are drawn by exactly the same radii as the similarly-marked arcs in the plan, Fig. 1; but I do not limit myself to this, as the proportion of radii may be slightly varied without destroying the continuity of the curve or the symmetry between its appearance in plan and end views. The shape of the ends of the casket A conforms with that of the ends of the cover B. C and D are raised portions of the cover B, put on for ornament, and their ends are all shaped in conformity with the end curves of the cover B, as seen in the drawing; but the inner end curves g and h of the reliefs C and D I prefer to make parallel with each other. In Fig. 4 the center e of the arc $d f$ lies at a point outside of the extended line $a d$ of the previous arc, thereby causing a break in the curve or a sharp corner at d , the effect being a different and less pleasing design.

What I claim as my invention is—

A design for caskets in which the cover, whether as seen in plan or in an end elevation of the casket, is formed into the curve constructed as shown and described, and the ends of the casket A and of the reliefs C D are curved symmetrically therewith.

JOHN NILSSON.
